BAR STOOL

George Kasparian, Los Angeles, Calif., assignor to Kasparians, Inc., Los Angeles, Calif., a corporation of California

Original design application Feb. 11, 1964, Ser. No. 78,598.
Divided and this application Oct. 22, 1965, Ser. No. 619

Term of patent 14 years

(Cl. D15—8)

The dominant features of my design reside in those portions shown in full lines on the drawing.

This application is a division of my earlier application Serial No. D.78,598, filed February 11, 1964, and now abandoned.

I claim:

The ornamental design for a bar stool, substantially as shown and described.
